[57] CLAIM

The ornamental design for a slide-in refrigeration unit, as shown and described.

DESCRIPTION

FIG. 1 is a partially exploded perspective view of the slide-in refrigeration unit, showing our new design;

FIG. 2 is a front elevational view thereof;

FIG. 3 is a front elevational view thereof, with the cover shown removed;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an environmental view thereof, being disposed at the lower portion of a storage unit with the cover removed; and,

FIG. 10 is another environmental view thereof, being disposed at the upper portion of a storage unit.

The broken line showing of the storage unit is for illustrative purposes only, and forms no part of the claimed design.
